UNITED STATES PATENT OFFICE.

GUSTAVE E. VILLARET, OF LEONIA, NEW JERSEY, ASSIGNOR TO THE AMERICAN PIN COMPANY, DIVISION SCOVILL MANUFACTURING COMPANY, OF WATERBURY, CONNECTICUT, A CORPORATION OF CONNECTICUT.

DESIGN FOR AN ADAPTER FOR LIGHTING FIXTURES.

Application filed February 12, 1926. Serial No. 16,509. Term of patent 3½ years.

To all whom it may concern:

Be it known that I, GUSTAVE E. VILLARET, a citizen of the United States, residing at Leonia, county of Bergen, and State of New Jersey, have invented a new, original, and ornamental Design for an Adapter for Lighting Fixtures, of which the following is a specification, reference being had to the accompanying drawing, forming part thereof.

In the drawing, Figure 1 is a plan view, and

Fig. 2 is a section on line 2—2, Fig. 1 of an adapter for lighting fixtures showing my new design.

I claim:

The ornamental design for an adapter for lighting fixtures, as shown.

GUSTAVE E. VILLARET.
